Primary Examiner — Amy C Wierenga**CLAIM**

We claim the ornamental design for a fitting, as shown and described.

DESCRIPTION

FIG. 1 is a front perspective view of the fitting in its environment with a pipe inserted in one end;
FIG. 2 is a front and top perspective view of the fitting;
FIG. 3 is a side view of the design shown in FIG. 2;
FIG. 4 is a top view of the design shown in FIG. 2;
FIG. 5 is a bottom view of the design shown in FIG. 2; and,
FIG. 6 is a cross sectional view of the design shown in FIG. 1 taken along line 6 and shown in use with a pipe having been inserted in each end.

The dash dot broken lines shown in the drawings illustrate environmental subject matter only that forms no part of the claimed design.

(Continued)

The dashed broken lines shown in the drawings illustrate portions of the fitting that form no part of the claimed design.
